UNITED STATES PATENT OFFICE.

FRED C. BAKER, OF PORTLAND, OREGON, ASSIGNOR TO MACBETH-EVANS GLASS COMPANY, OF CHARLEROI, PENNSYLVANIA, A CORPORATION OF PENNSYLVANIA.

DESIGN FOR A GLOBE.

Application filed March 20, 1929. Serial No. 30,534. Term of patent 7 years.

To all whom it may concern:

Be it known that I, FRED C. BAKER, a citizen of the United States, residing at Portland, in the county of Multnomah and State of Oregon, have invented a new, original, and ornamental Design for Globe, of which the following is a specification, reference being had to the accompanying drawing, forming a part thereof.

The figure is a side view of a globe showing my new design.

I claim: The ornamental design for a globe, as shown.

FRED C. BAKER.
